SYSTEM AND METHOD FOR HEATING
DYNAMO-ELECTRIC MACHINES

Eric Brown, Baden, Switzerland, assignor to
Aktiengesellschaft Brown Boveri & Cie., Baden,
Switzerland, a joint-stock company of Switzerland

Application December 24, 1929, Serial No.
416,307, and in Germany December 24, 1928

5 Claims. (Cl. 171—252)

This invention relates to improvements in electric current generators and, particularly, to means for maintaining large generators in condition for substantially instantaneous starting at full load. 5 Large generators cannot be placed under full load immediately upon starting for the reason that the several portions of the generator heat up at different rates, thereby causing stresses and strains in the generator structure. The copper 10 portions embedded in the iron of the rotor heat up more quickly than the iron, partly because of the heat-insulating qualities of the coverings of the copper. Such action, especially when frequently repeated, materially shortens the life of 15 the copper insulation. A further difference in the heating effect is likewise apparent when large generators are quickly started, in that the circumference of the rotor reaches the full load operating temperature before the core thereof has been 20 materially heated. Such difference in temperature conditions causes stresses in the materials and may even cause bending of the shaft, thereby giving rise to destructive vibrations.

It is, therefore, among the objects of the present invention to provide means for maintaining generators, and particularly large generators, in such condition as will permit quick starting and quick full-load application thereon.

Another object of the present invention is to provide means for maintaining generators in such heated condition as to permit full-load operation thereof substantially immediately after starting.

Another object of the invention is to provide means for preheating and automatically maintaining generators at the proper temperature for full-load operation immediately upon starting by the use of portions of the generator structure itself in combination with exterior heat sources.

Objects and advantages, other than those above set forth, will be apparent from the following description and the accompanying drawings, in which

Figure 1 shows a side elevation of one embodiment of the invention using a heat source external to the generator for maintaining the temperature thereof.

Fig. 2 shows a modified form of the invention, also in side elevation, which is similar to that shown in Fig. 1.

Fig. 3 is a modified embodiment of the invention in which portions of the generator to be heated are utilized as heat sources in addition to means for supplying heat from external sources thereto, and

Fig. 4 illustrates one manner of using portions of the generator as a supplemental heat source.

Referring more particularly to the drawings by characters of reference, the reference numeral 6 indicates a generator which is enclosed in a substantially gas-tight manner, and to which are connected supply conduits 7, 8 having a common portion and connecting with the generator 6 at the ends thereof. A discharge conduit 9 is connected with the generator structure at substantially the central portion thereof. The supply conduits 7, 8 and the discharge conduit 9 are connected by means of a blower 11 driven by a suitable source of power, such as a motor 12, for the purpose of maintaining the heat-carrying medium 70 within the supply conduits 7, 8, within the generator housing and within the discharge conduit 9, in circulation. The gases circulating through the generator and the various conduit connections therewith are heated by means of a 75 heat-exchanger 13 or a heating resistance 14 arranged in the common portion of the supply conduits 7, 8. The heat-exchanger 13 may be supplied for heating purposes with steam or hot water or any suitable heat-carrying medium from a 80 suitable source. It will, of course, be understood that both or either the heat-exchanger 13 or the heating resistance 14 may be connected to provide for transmission of heat to the gases circulating through the supply conduits, the generator, and 85 the discharge conduit circuit under the action of the blower 11, as above set forth.

If it is desired to provide means for automatically maintaining the generator 6 at a predetermined temperature, a branch pipe 16 is connected with the common portion of the supply conduits 7, 8, immediately behind the heat-exchanger 13 and the heating resistance 14. The branch pipe 16 is connected with a blower 17, operated by a suitable source of power such as 90 a steam turbine 18, for maintaining the gases within the generator in constant circulation by discharging the same through a discharge pipe 19 connecting with the discharge conduit 9. A heating resistance 21 is shown arranged within the 100 discharge pipe 19, and is connected by means of a suitable switch 22 to a regulating rheostat 23. The amount of the rheostat resistance connected into the heating circuit is determined by the operation of a suitable thermostatic element 24 105 within the by-pass pipe 25 between the branch pipe 16 and the discharge pipe 19.

In case it is desired to utilize the exhaust steam from the turbine 18 as the heating medium, a thermostatically-operated valve, indicated at 26, 110

is connected with the exhaust line 27 from the turbine 18 and the heating resistance 21 is replaced by a heat-exchanger of any suitable character.

5 It will be seen that the above embodiment of the invention provides means for maintaining the gases circulated about the stator and rotor of a generator in a preheated condition either by manual operation of the heat-exchanger 13 10 or the heating resistance 14, or by thermostatic operation of the heating resistance 21 or a heat-exchanger inserted in the discharge line 19 in place thereof.

When the automatic apparatus is used for 15 controlling the temperature, some of the air from the outlet side of the blower 11 takes the path to the right through the branch pipe 16, through the blower 17, and thence by way of the discharge pipe 19 to the heating resistance 21, 20 whereupon it mingles with the air being discharged from the generator 6 and passes with this air through the blower 11. The amount of air passing through this circuit, and the amount of heat imparted thereto by the resistance 21, 25 are sufficient to maintain the air, circulated through the generator, at the required temperature. The air passing through the by-pass pipe 25 subjects the thermostatic element 24 to substantially the temperature of the air as it is 30 forced into the generator, and this element operates to effect variation of the temperature of the heating resistance 21 inversely proportionally to variations in the air temperature at this point.

35 Figure 2 shows a modification of the present invention in which a generator 28, driven by a turbine 29, is heated to maintain the generator in such condition as to be available as a reserve machine for instantaneous starting. In this embodiment, a heat-exchanger 31, supplied with a heating medium from a suitable source, is connected with the generator 28 and with a blower 32 for the purpose of circulating a heat-carrying medium therethrough.

45 Connections are made with the pipe leading from the generator 28 to the inlet of the blower 32 for discharging part of the heat-carrying medium through a second generator 33, also driven by turbine 29, for the purpose of maintaining this generator also in the proper heated 50 condition necessary for instantaneous full-load operation upon starting. Connections are so arranged that the heat-carrying medium is supplied to the generator 33 at one or more points, 55 and is abstracted therefrom at a different point by means of a circulating blower 34 connected between the inlet and outlet connections between the generator 33 and the circulatory system connected with the generator 28. This 60 method of maintaining both generators in a heated condition is particularly valuable for use in central-operated stations, or for ships which are provided with electrically operated power transmission, inasmuch as the rotors of the generators are usually slowly rotated so that the 65 same are maintained in a uniformly heated condition which permits the application of the full load thereon immediately upon starting.

The arrangement shown in Fig. 3 is similar 70 to that shown in Fig. 1, with the exception that the windings of the rotor itself are utilized as heating resistances to aid in maintaining the temperature of the generator at the predetermined value. For this purpose, the slip rings 36 75 of the generator 6 are connected with a suitable

source of current such as a generator 37 driven by a suitable source of power, such as a turbine 38. The amount of current supplied to the windings of the rotor is determined by means of a regulating resistance 39 controlled, in dependence on the temperature of the gases circulating within the generator housing, by means of a thermostatic element 41 operating a system of levers 42 for the purpose of cutting resistance into or out of the circuit. For the purpose of facilitating the connection of the windings of the rotor for use as heating resistances, the ends of the several phases 46 and 47 are brought out in such manner that they may be connected in series by means of switches 48.

80 It will be seen that the present invention provides means whereby a generator may be maintained at substantially the operating temperature for the purpose of making it possible to bring the same to full-load immediately after starting. According to the present invention, this result is attained either by the use of external heat sources for transmitting heat to gases circulated through the generator, or by a combination of such external heat sources with the use of the 85 rotor windings as heating resistances. It will likewise be seen that the temperature of the generator may be regulated either manually or automatically in the case of either the use of an external heat source or the combination of the external heat source with the rotor windings as 90 heating resistances.

95 Although but a few embodiments of this invention have been illustrated and described, it will be understood that various other embodiments are possible, and that various changes may be made without departing from the spirit of the invention or the scope of the appended 100 claims.

105 The invention claimed is:

110 1. In a system for maintaining an electric current generator in immediately operative condition, a supply conduit connected with the generator, a discharge conduit connected with the generator, means for circulating a heat-carrying medium through said conduits, a source of heat for heating the heat-carrying medium, and thermostatic means for controlling the amount of heat-transmitted to the heat carrying medium from 115 said heat source.

120 2. In the art of operation of a dynamo electric machine, the method of maintaining the temperature throughout the machine structure substantially constant, during non-operation thereof, at substantially the temperature developed 125 during normal operation; said method comprising supplying a heat-carrying medium to the machine structure, and increasing the temperature of said medium when the temperature throughout the machine structure decreases from 130 substantially the temperature developed during 135 normal operation of the machine.

3. In a system of the character described, a dynamo electric machine, means for supplying a heat-carrying medium to said machine comprising 140 a closed circuit including the machine, means operable independently of said machine for causing said medium to circulate around said circuit, means operable independently of the condition of operation of said machine for imparting heat 145 to said medium, and means for controlling said medium-heating means responsive to variations in the temperature of said medium, at a given point in said circuit, from a predetermined degree of temperature.

4. In a system of the character described, a
dynamo electric machine, means for supplying a
heat-carrying medium to said machine comprising
a closed circuit including the machine, means
5 operable independently of said machine for caus-
ing said medium to circulate around said circuit,
and means comprising an electrical resistor and
operable independently of the condition of oper-
ation of said machine for imparting heat to said
10 medium.

5. In a system of the character described, a
dynamo electric machine, means for supplying a

heat-carrying medium to said machine comprising
a closed circuit including the machine, means
operable independently of said machine for caus-
ing said medium to circulate around said circuit,
and means comprising an electrical resistor and
operable independently of the condition of opera-
tion of said machine for imparting heat to said
medium, said resistor being embodied in said
machine and forming at least part of the operat-
ing windings thereof.
